UNITED STATES PATENT OFFICE.

EJNAR ALFRED MEYER, OF CLIFTON, BRISTOL, ENGLAND.

PROCESS FOR PRESSING YEAST.

1,268,865.

Specification of Letters Patent. Patented June 11, 1918.

Application filed November 12, 1917. Serial No. 201,571.

To all whom it may concern:

Be it known that I, EJNAR ALFRED MEYER, a subject of the King of Denmark, residing at 38 Canyge Square, Clifton, Bristol, England, have invented a new and useful Improved Process for Pressing Yeast, of which the following is a specification.

This invention relates to an improved process for pressing yeast, in which the liquid containing the yeast is separated from it by air pressure.

In the manufacture of yeast as at present practised filter presses are employed which cost considerable sums and require a great deal of labor and care in working. By the present process an increased yield of yeast is obtained and the yeast cells are not damaged, and the process is less costly.

According to this invention the yeast is pressed by being deposited on the surface of a revolving drum from which the air is exhausted and which extends into a vessel containing yeast. The dry outer layer of the deposited yeast is removed by a knife, leaving the damp inner layer on the drum, which inner layer prevents the vacuum from being broken. In order, however, to insure that the vacuum is not broken, I arrange beneath and in proximity to the knife a perforated pipe which supplies liquid containing yeast to the drum.

The accompanying drawings illustrate an apparatus by which my invention may be carried out. Fig. 1 is a side elevation, Fig. 2 a plan and Fig. 3 an end elevation.

The liquid containing yeast is stored in a vessel *a* from which it is supplied to a tank *b* through a pipe *c* which extends the length of the tank and is perforated at the side nearest the drum, the flow from the vessel *a* being regulated by cocks *d* and *e*. A perforated conical drum *f*, whose surface is covered with a filter cloth or like material and whose ends are closed, is mounted on trunnions *g* supported by bearings *h*. The drum *f* is revolved quickly when the drum is being sprayed before the removal operation by means of a toothed wheel *i* gearing with another toothed wheel *j* on a shaft *k* which is revolved by a belt running on a

pulley *l*, or slowly during the removal operation through a toothed wheel *m* on a shaft *n* having on it another toothed wheel *o* in gear with a pinion *p* on a shaft *q* on which shaft is a toothed wheel *r* gearing with a pinion *s* on a sleeve *t* which is revolved by a belt running on a pulley *u*. The drum *f* as it revolves passes through the liquid in the tank *b* and at the same time liquid from the perforated portion of the pipe *c* is sprayed upon the surface of the drum. As the air is exhausted from the drum *f* through a pipe *v* passing through the trunnions *g* a layer of yeast is deposited on the exterior surface of the drum.

The yeast is removed from the drum by means of a knife *w* resting on a bar *x* and carried at the ends of arms *y* mounted on eccentrics at the ends of a shaft *z*, so that the distance of the knife from the drum *f* can be regulated by means of a handle *aa* connected to the shaft *z*. On the opposite side of the apparatus to the knife *w* is a perforated pipe *A* by which water may be supplied to the surface of the drum *f* when desired.

This apparatus may be worked continuously without the vacuum being broken as the knife *w* is so arranged that the dry outer layer of the yeast deposited upon the drum *f* only is removed and any tendency of the vacuum to break is immediately arrested by the liquid containing the yeast which is sprayed on to the drum through the perforations in the pipe *c* which is situated below and in close proximity to the knife *w*.

What I claim is:

1. A process of pressing yeast, consisting in depositing yeast in liquid form upon the surface of a revolving drum, then exhausting air from the drum to solidify the yeast on the drum, and then removing the relatively dry outer layer of the deposited yeast leaving a relatively damp layer on the drum to prevent the breaking of a vacuum within the drum.

2. A process of pressing yeast, consisting in depositing the yeast from a vessel containing it upon the surface of a revolving drum, then exhausting air from the drum,

and then removing the relatively dry outer layer of the yeast and leaving a relatively damp inner layer on the drum to prevent the breaking of the vacuum within the drum.

5 3. In the process of pressing yeast, supplying liquid containing yeast to a vessel into which a revolving drum extends, ex-

hausting the air from the drum, removing the outer layer of yeast from the surface of the drum and spraying liquid containing yeast upon the surface of the drum in proximity to the part from which the deposited yeast is removed.

EJNAR ALFRED MEYER.
